Primary Examiner — Elizabeth Albert(74) Attorney, Agent, or Firm — Junea & Mitchell(57) CLAIM

The ornamental design for a planter, as shown and described.

DESCRIPTION

FIG. 1 is top perspective view of a planter showing my new design;

FIG. 2 is a bottom perspective view thereof;

FIG. 3 is a top plan view thereof;

FIG. 4 is a bottom plan view thereof;

FIG. 5 is a side view thereof; and,

FIG. 6 is an end view thereof.

The broken lines in the drawings are included for the purpose of showing portions of the planter that form no part of the claimed design.
